Primary Examiner — George D. Kirschbaum*Assistant Examiner* — Joseph J Kukella(57) **CLAIM**

The ornamental design for a toy, as shown and described.

DESCRIPTION

Fig. 1.1 is a perspective view of the toy according to an embodiment of the present invention;

Fig. 1.2 is a front view of the toy of Fig. 1.1;

Fig. 1.3 is a left view of the toy of Fig. 1.1;

Fig. 2.1 is a perspective view of the toy according to an embodiment of the present invention;

Fig. 2.2 is a front view of the toy of Fig. 2.1; and

Fig. 2.3 is a left view of the toy of Fig. 2.1.

The right view of Figures 1.1 and 2.1 have been omitted because they are the same as the left views.

The back views of Figures 1.1 and 2.1 have been omitted because they are the same as the front views.

1 Claim, 6 Drawing Sheets(56)
